(57) **CLAIM**

The ornamental design for a combined pen and pen stand, as shown and described.

DESCRIPTION

FIG. 1 is a perspective view of the combined pen and pen stand of the present invention shown with the pen inserted into the pen stand.

FIG. 2 is a left side plan view of the combined pen and pen stand of the present invention.

FIG. 3 is a right side plan view of the combined pen and pen stand of the present invention.

FIG. 4 is a front end plan view of the combined pen and pen stand of the present invention.

FIG. 5 is a back end plan view of the combined pen and pen stand of the present invention.

FIG. 6 is a top plan view of the combined pen and pen stand of the present invention.

FIG. 7 is a bottom plan view of the combined pen and pen stand of the present invention; and,

FIG. 8 is a perspective view of the combined pen and pen stand of the present invention shown with the pen removed from the pen stand.

The broken lines in the drawings depict portions of the combined pen and pen stand that form no part of the claimed design.
